UNITED STATES PATENT OFFICE.

RALPH P. TARBUTTON, OF LIMA, OHIO.

AUTOMATIC REVERSIBLE DRIVING-CHUCK.

1,341,085.

Specification of Letters Patent.

Patented May 25, 1920.

Application filed March 29, 1919. Serial No. 286,058.

To all whom it may concern:

Be it known that I, RALPH P. TARBUTTON, a citizen of the United States, residing at Lima, in the county of Allen and State of Ohio, have invented certain new and useful Improvements in Automatic Reversible Driving-Chucks, of which the following is a specification, reference being had therein to the accompanying drawings.

10 This invention relates to an automatic reversible driving chuck, and has for its object the construction of a chuck that is provided with simple and efficient means for allowing the reversing of the chuck to release the tool or member engaged by the jaws, or to allow the jaws to grip a member or tool for operating the tool gripped in a different direction from that direction in which the tool may formerly have been 20 driven.

With this and other objects in view, my invention comprises certain novel constructions, combinations, and arrangements of parts as will be hereinafter specifically described, illustrated in the accompanying drawings, and more particularly pointed out in the appended claim.

In the drawings,

Figure 1 is a view in elevation and partly 30 in section of a chuck constructed in accordance with the present invention, while

Fig. 2 is a section taken on line 2—2, Fig. 1, looking in the direction of the arrows.

Fig. 3 is a view in elevation of a chuck 35 constructed in accordance with the present invention.

Fig. 4 is a sectional view taken on line 4—4, Fig. 1, looking in the direction of the arrows.

40 Fig. 5 is a perspective view of the locking ring.

Fig. 6 is a rear view of the gripping collar.

Fig. 7 is a side view of the jaw guide or 45 holder, showing the gripping collar assembled therewith.

Fig. 8 is a fragmentary view of the head of the chuck.

Referring to the drawings by numerals, 1 50 designates the shank and 2 the head of the chuck. The head is reduced at 3 (Fig. 8) producing an annular shoulder 4, upon which is rotatably mounted the locking ring 5 which is roughened or knurled upon its 55 outer face for facilitating the gripping thereof; this collar 5 is provided with a

transversely-constructed V-shaped notch 6, for the purpose hereinafter described.

The head 2 is provided with a socket having side walls 7, 7 bored eccentrically, and 60 between walls 7, 7 are bearing surfaces 8, 8 arranged directly opposite each other; these surfaces 8 are cam-like in their function for forcing the sliding jaws 9 farther into the jaw holder 10.

65 The jaw holder 10 is hollow, and is provided at opposite sides with jaw-receiving slots 11; each slot 11 is provided with an inwardly beveled end 12 (Figs. 1 and 7). Each jaw 9 is provided with similarly-constructed ends, producing jaws of substantially wedge-shape, whereby the jaws will not be permitted to drop entirely into the jaw holder 10, but the jaws 9 can move outwardly upon the holder as shown in dotted 70 lines (Fig. 4) for releasing the tool or object formerly held between the jaws.

75 Each jaw is beveled at 13 at its outer corner so that any tool or object to be gripped of a round structure can be readily 80 forced between the jaws. The jaws have longitudinally-extending teeth 14 formed thereon, which teeth will enable the jaws to tightly grip an object placed therebetween for causing the object to rotate forwardly 85 or backwardly, so to speak, after the jaws have been moved to the position shown in Figs. 1 and 4. If transverse teeth are 90 formed upon the jaws, or teeth at right angles to the position of teeth 14, then the jaws can be used for gripping an object to be pulled, when it is desired to use the chuck as a pulling tool; there is no invention in arranging the teeth 14 longitudinally of the 95 jaws, or in arranging the teeth transversely of the jaws, but the arrangement of the jaws longitudinally permits the jaws to grip an object to be rotated, and the arrangement of the teeth transversely permits the jaws to grip an object to be pulled.

100 A gripping collar 15 is placed against the inner end of the jaw holder 10, and by means of pins 16 extending through apertures 17 of the collar, and also extending into suitable sockets formed in the holder 10, this collar 105 can be secured upon the inner end of the holder 10 against independent rotary movement; the collar 15 is provided with a gripping surface or teeth 18 for holding the inner end of an object or tool that has been 110 run into the chuck, while the head 2 and shank 1 of the chuck are slightly rotated.

In the outer face of the holder 10 is formed an elongated slot 19, which slot extends around the holder a suitable distance and is provided for receiving alternately the inner 5 ends of pins 20. Each pin 20 is slidably mounted in an enlarged aperture 21 formed in the reduced portion of the head 2, upon which reduced portion is rotatable ring 5. The inner end of each aperture is reduced in 10 size to substantially the size of the pin 20; the pin 20 has a tapering or wedge-like outer head 22 that rides into the V-shaped notch 6 of ring 5. Around each pin 20 is positioned a coil spring 23 which exerts an outward pressure or pull upon the pin for holding the same in the notch 6, causing the inner end of the pin to be moved from engagement with the jaw holder 10, but when the ring 5 is moved so as to force the head 22 of 15 a particular pin downwardly, then the inner end of the pin is forced into the elongated socket or slot 19, causing the jaw holder to be limited in its rotary movement, locking the jaw holder in one direction against further movement at the desired position, and at the same time the jaws 9, by reason of the cam-like bearings 8, are forced downwardly to their limit into the holder 10 for gripping 20 an object securely that may be between the jaws. If it is desired to grip and rotate an object held by the jaws 9 in the opposite direction to that position shown in Fig. 4, all 25 that is necessary is to rotate sleeve 5 so that the socket 6 will move over the left-hand pin 20 (Fig. 4), allowing the head of this pin to ride up into the notch 6, thereby allowing the holder 10 to be rotated for causing the jaws 9 to move to the dotted positions in the chuck head, allowing the jaws 30 to slide out sufficiently to release the tool or object gripped. This turning of the holder 10 so as to position the jaws 9, as shown in dotted lines in Fig. 4, is caused by turning the tool backward which is held between the 35 jaws. After the jaws are in the position shown in dotted lines, Fig. 4, the tool can be inserted between the jaws, then the chuck turned so as to place the outer ends of the 40

50 jaws directly against the bearings 8, forcing the jaws against the object to be worked upon and at the same time one of the pins will be extending at its inner end into the groove or socket 19, locking the chuck head and the jaw holder against further independent rotary movement, so that, in the desired direction, the jaw holder and the chuck head and the shank will rotate together. 55

A cap ring 24 is placed over the outer end of head 2 and the outer end of jaw holder 10 (Figs. 1, 2, and 3), and this cap ring is held in position by suitable fastening means as screws 25 (dotted lines). The central bore or opening 26 of cap ring 25 is slightly larger in diameter than the opening in the 60 jaw holder so as to afford a ready entrance of the tool or object to be worked upon when entering the jaw holder 10, between the jaws 9.

In the accompanying drawings and in the 70 foregoing description, I have preferably illustrated and described the preferred form of my invention, but certain minor changes or alterations may appeal to one skilled in the art to which this invention relates, in 75 manufacturing my chuck, and, therefore, I reserve the right to make such minor alterations and changes as shall fairly fall within the scope of the appended claim.

What I claim is:

80
In a device of the class described, the combination of a head provided with a central hollow body having eccentric faces and with oppositely-positioned bearings constituting cam surfaces, a holder in said head and provided with slidable jaws, said jaws adapted to engage at their outer ends said cam bearings for forcing the jaws to their furthermost inner position, and spring-pressed pins carried by the head and alternately engaging 85 the holder for fastening the holder against independent rotary movement with respect to the head in different directions.

90
In testimony whereof I hereunto affix my signature.

RALPH P. TARBUTTON.
